UNITED STATES PATENT OFFICE.

HARRY A. HOOD, OF ST. LOUIS, MISSOURI, ASSIGNOR, BY DIRECT AND MESNE ASSIGNMENTS, TO H. S. H. MANUFACTURING COMPANY, INC., OF ST. LOUIS, MISSOURI, A CORPORATION OF MISSOURI.

RADIATOR-FILLER CAP.

1,286,320.

Specification of Letters Patent.

Patented Dec. 3, 1918.

Application filed July 29, 1915. Serial No. 42,660.

To all whom it may concern:

Be it known that I, HARRY A. Hood, a citizen of the United States, and resident of St. Louis, Missouri, have invented certain new and useful Improvements in Radiator-Filler Caps, of which the following is a specification containing a full, clear, and exact description, reference being had to the accompanying drawings, forming a part hereof.

10 My invention relates to improvements in radiator filler caps, wherein I employ a ring or adapter bearing on its inner face cam shaped projections and having means such as threads for connection with the filler spout, and a cap carrying spring pressed pins for co-operation with said cam faced projections to lock the cap in place.

15 The object of my invention is to improve the construction of cap shown and described 20 in my application for Letters Patent of the United States filed July 6, 1915, and serially numbered 38,285, to the end that the cap may be adapted for use in connection with the ordinary filler spouts.

25 With the above object in view, my invention consists in certain novel details of construction and arrangement of parts herein-after fully described, pointed out in my claim, and illustrated by the accompanying 30 drawings, in which—

Figure 1 is a front elevation of a radiator filler spout having an internally threaded flange at its top equipped with a cap embodying my invention, said cap and the upper end of said filler spout being shown in section;

35 Fig. 2 is an inverted plan of the ring or adapter showing the arrangement of the cam shaped elements;

40 Fig. 3 is a fragmental vertical sectional elevation of the upper end of the filler spout shown in Fig. 1, and the ring bearing the cam faced elements, the view being taken substantially at right angles to Fig. 1;

45 Fig. 4 is a view similar to Fig. 1, showing the device as constructed and applied to a filler spout having an outside thread; and

Fig. 5 is an inverted plan of the ring and cams shown in Fig. 4.

50 Referring by numerals to the accompanying drawings,

6 designates the radiator and .7 the filler spout, of the type having at its upper end an internally threaded flange 8.

The reference numeral 9 designates a ring 55 provided with external threads 10 for connection with the internally threaded flange 8 of the filler spout, and on its interior projecting laterally from the inner perimeter thereof are the diametrically opposite projections 11 whose lower faces incline from end to end, the one lower face inclining in an opposite direction from the other face, and toward the lowermost point of each cam face, *i. e.*, the lower inclined faces just described, there is a seat 12 and next adjacent said seats are the posts 13. By preference and as shown these posts are next adjacent the end of the projections, and said ends form shoulders 14, whose functions will be 65 explained later. The numeral 15 designates a crown cap bearing on its upper surface the radially disposed wings 16 which facilitate its manipulation. Formed through the cap is a non-circular opening 17, which is designed to receive the upper end of a non-circular stem 18, which stem carries at its upper end a reduced and threaded extension 19 arranged to receive a retaining nut 20, whereby the crown cap is secured to the non- 70 circular stem 18. 75

The numeral 21 designates a collar having a non-circular opening therethrough, and which is arranged for axial movements upon the stem 18, and which collar carries the 80 radial pins 22, which are designed to co-act with said cam faced elements to lock the crown cap to the filler spout.

At the lower end of the stem 18 I form a stop 23, the form of stop shown in the drawings being a split ring inserted through an opening formed through the stem and by preference I connect with the split ring a short chain whose other end is connected with a stud 24 secured within the filler spout, whereby at all times the crown cap and parts carried thereby may not be bodily removed and lost from the filler spout. 95

Embracing the stem and impinging between the split ring or stop 23 carried by the 100 stem and the collar 21 is an extensible coil spring 25, which tends to exert a downward

pressure upon the stem and an upward pressure against the pins 22, to the end that the crown cap is spring-held in closed position.

In the form of device illustrated in Fig. 4, 5 the spout 26 has external threads at its upper end, thus necessitating a slightly different form of ring or adapter 27.

In this form of ring there is an internally threaded flange 28 carrying at its top an in-turned flange 29, from which depend the cam faced elements 30, which are identically like the cam faced elements of the form of device shown in Figs. 1, 2 and 3.

The reference numeral 31 designates a 15 flat topped cap having a depending flange 32 which embraces the upper end of the ring or adapter 27, and like the crown cap shown in Fig. 1, the cap 31 is provided with a non-circular opening to receive the non-circular 20 stem 18, which in all particulars is the same as the stem previously described, and is arranged for connection with the cap 31 by means of a retaining nut 20 as in the other form of device.

25 Assuming a cap is locked to the filler spout and it be desired to remove the same therefrom, the cap is grasped and rotated, thereby unseating the pins 22 from the seats 12 and when said pins are brought to the 30 ends of the cam faces the cap with the stem and said pins may be lifted from position covering the spout.

It is to be noted here that the operation is identical in each of the forms shown, hence 35 the description of the operation of one will cover the operation of the other.

To replace the cap it is first placed in a 40 position so that the pins 22 will be brought over the gaps between the ends of the cam faced elements, where they will be in a position to be engaged beneath said cam faces at the highest points of said cam faces; the 45 cap is then rotated, thereby causing the pins to ride the cam faces, the spring allowing the pins to yield as they are advanced over the cam faces, until the pins find the seats 12 where the spring again acts to not only tend to hold the pins seated, but also to hold the crown to a non-leaking position on the filler 50 spout. The posts 13 perform the function of stops to limit the movement of the pins in their rotary movement beyond the seats in applying the cap, and in removing the cap said posts limit the movement of the pins in

an opposite direction beyond the ends of the 55 flanges on which the posts are formed.

To facilitate the placement of the ring or adapter the crown is placed in position wherein the pins abut the shoulders or ends of the cam faced elements, so that upon a rotation of the crown with its stem and said pins, the ring may be rotated so that its threaded connection with the filler spout may be accomplished with a minimum of effort, and without the employment of extraneous 60 manipulative devices.

Having thus described my invention, what I claim as new therein and desire to secure by Letters Patent of the United States therefor, is—

A radiator filler cap comprising a filler tube provided on its upper end with screw threads, a ring provided with a screw threaded flange arranged for threaded connection with said tube and with a parallel 75 flange spaced apart from the first mentioned screw threaded flange a distance sufficient to permit the filler tube end to be seated between the flanges, said second mentioned flange being provided with cam faces inclined in opposite directions and spaced apart, there being a curved seat formed in each cam face diametrically disposed to each other, said curved seats terminating in shoulders, a cap mounted on said ring, an 80 angular opening formed in said cap, an angular stem positioned in said opening, a nut carried by said stem and adapted to be seated against the top of the cap for limiting the downward movement of the stem, a collar provided with an angular bore mounted on said stem, oppositely disposed arms 85 curved in cross section carried by said collar, said arms adapted to move over said cam surfaces and to be seated in the said curved 90 seats and to be easily removed therefrom, a pin located in the lower end of said stem and a coil spring mounted on said stem between the collar and pin, the said ring, cap, stem, 95 collar and spring being rotatable and removable together.

In testimony whereof I have signed my name to this specification in presence of two subscribing witnesses.

HARRY A. HOOD.
